ROLL MILL FOR GRINDING LIQUID AND PASTY MATERIAL

Friedrich Ploberger, Vienna, Austria

Application August 22, 1952, Serial No. 305,841

Claims priority, application Austria August 24, 1951

4 Claims. (Cl. 241—222)

This invention relates to a roll mill for grinding liquid and pasty material.

Grinding mills having one or several rolls have been suggested already in which one or several auxiliary rolls, to assist the grinding process, are arranged in the feed hopper and being driven in the opposite sense as the main or grinding roll are forced against the periphery thereof. In this arrangement the auxiliary rolls rotate with their peripheral surface in the material to be ground, which is situated in the feed hopper, and thus interfere with the uniform access of the material to the main rolls. For this reason the auxiliary rolls have been provided in a chamber separated from the feed hopper. The auxiliary rolls carried in correspondingly designed bearings were forced by special adjustable means against the grinding roll. This requires supervision during operation. If the pregrinding operation between grinding roll and auxiliary roll is not sufficiently effective only the sufficiently ground part of the material to be ground can be engaged by the bar. For this reason the space between the grinding roll, auxiliary roll, and bar has been connected to the feed hopper by a duct extending round the auxiliary roll, to permit of several passes of the material between the grinding and auxiliary rolls.

The known constructions do not sufficiently allow for the fact that particularly in the case of viscous or pasty substances the rolls are hardly wetted or are wetted not at all, the grinding operation being interrupted if the peripheral speed of the rolls is increased beyond a certain limit. The output of the mill, however, depends also on the peripheral speed of the grinding roll, which controls the auxiliary roll. For this reason high speeds are desirable.

The invention relates to a roller mill for grinding liquid and pasty material and has as its object, on the one hand, to enable high rotary speeds without disadvantage and, on the other hand, to provide for forcing the auxiliary roll under uniform pressure against the main roll, without a special device. This is achieved in that the auxiliary roll lies loosely on the main roll, under its own weight, and is secured against travelling around the main roll, and that the auxiliary roll has coordinated therewith an applying device for feeding the liquid or pasty material to be ground, in the form of liquid filaments of controllable thickness. The liquid filaments distribute evenly on the surface of the auxiliary roll, which is effective as an edge runner, to form a layer of the desired thickness, which is transferred to the main roll at the point of contact of the two rolls. Thus rotation of the roller within the material to be ground is prevented and wetting difficulties are eliminated entirely.

The construction according to the invention may be developed to enable a repeated passage of the material to be ground, as in the known mills mentioned hereinbefore, and an additional mixing thereof. This is achieved also in a very simple manner in that the auxiliary roll loosely lies against a wall serving as a stop for the grinding bar and together with said wall and the grind-

2

ing roll defines a chamber in which the material to be ground is homogenized before being discharged from the bar. Hence, the material to be ground is subjected to pregrinding between the two rolls, to a continuous kneading in the chamber, without use of the previously employed stirring tools, and to a final grinding between the bar and the main roll. When more material to be ground is introduced into the chamber than is discharged between the bar and the main roll, the excess of material to be ground will escape from the filled chamber at the point of contact of the auxiliary roll with the wall, to be preground additionally at this point, and will be reintroduced into the chamber. Thus the grinding efficiency can be substantially increased.

In the drawing an example of the subject of the invention is shown schematically in vertical section. The shaft 1 has firmly arranged thereon the main roll 2, which is driven in the direction of the arrow 2', and in the usual manner performs a reciprocating motion too. An auxiliary roll 3 lies under its own weight loosely on the roll 2, and while secured against travelling around the main roll 2 laterally bears against a wall 4, which serves as a guide for the bar 5, and is hollow to supply cooling water for carrying off the working heat. The bar 5 is forced against the wall 4 by several mutually spaced, two-armed levers 7, rotatable about a pivot 6. To this end, set screws 8 with lock nuts 9 are provided. The spacing of the end face of the gate 5 from the main roll 2 (entrance gap) and thus the desired degree of fineness of the grinding operation, can be altered by the set screws 10, which can be secured in position by the lock nut 11. With the wall 4 and the main roll 2, the auxiliary roll 3 defines a cavity 12. Above the auxiliary roll a reservoir 13 for the material to be ground is provided. Several mutually spaced discharge pipes 14 only one of which is shown in the drawing, with cocks or outlets 15 to control the downflow or thickness of the filaments of material to be ground, are provided at the trough-shaped bottom of the reservoir. The pipes 14 are arranged above and along the auxiliary roll 3 so that the liquid filaments of the material to be ground come on top of the roll 3, where they distribute evenly over the peripheral surface thereof and during the rotation of the roll 3 in the sense of the arrow 3', effected by the main roll, are transferred to the main roll in the form of an even layer. Between the points of contact of the two rolls, the material to be ground is pretreated as in an edge mill, passed into the cavity 12 and thereafter to the bar 5, where it is allowed to pass only when the desired degree of fineness has been reached already, whereas the rest of the material to be ground is dammed back so that the space 12 progressively fills with material to be ground, which under the effect of the rotation of the two rolls is subjected to kneading. Material to be ground which is supplied into the cavity 12 in excess is additionally ground at the point of contact of the roll 3 with the wall 4 and then returns to the cavity 12; thus the grinding effect is increased and the passage is accelerated when the degree of fineness of the material to be ground has been achieved.

The material to be ground which has passed from the main roll through the bar is stripped off in the conventional manner by a knife and enters the receiver. To preclude in any case a splashing away of the material to be ground, the roll 3 is surrounded by a hopper-like container 16, which is not filled with material to be ground, as contrasted with the known roll-type grinding mills. Tests have shown that the grinding efficiency can be increased substantially with the novel grinding mill as compared with the known mills, because the rotary speed of the main roll can be increased greatly without disturbing the operation and because in addition to being ground

3

between the two rolls the material to be treated is ground at the point of contact between the auxiliary roll 3 and the wall 4, and the material to be ground which is enclosed in the cavity 12 is subjected to rapid homogenization. If desired, the auxiliary roll can be movable up and down in a guide so as to be secured against travelling around the main roll. Pasty material can be fed also by separate conveyor means, which feed the material to be ground to the main roll by pressure.

I claim:

1. In a roll mill for grinding liquid stock, the combination comprising a main roll, an auxiliary roll loosely supported on the main roll, means engaged by the auxiliary roll preventing same from traveling around the main roll and means feeding the liquid to be ground in 15 filaments to the auxiliary roll.

2. In a roll mill for grinding liquid stock the combination comprising a main roll, an auxiliary roll loosely supported above the main roll, means engaged by the auxiliary roll and preventing same from traveling around 20 the main roll, means feeding the liquid to be ground in filaments to the auxiliary roll, and means connected to the feeding means and controlling the thickness of the filaments.

3. In a roll machine for grinding liquid stock, the combination comprising a main roll, an auxiliary roll loosely supported on the main roll, means engaged by the auxiliary roll and preventing same from traveling around the main roll and discharge pipes feeding liquid to be 25 ground in filaments to the auxiliary roll and each having 30 an outlet.

4. A roll mill comprising a main roll, a grinding bar adjacent to the main roll, a wall in guiding engagement with said grinding bar, an auxiliary roll loosely supported by said main roll and bearing against said wall, said wall, 5 and the peripheries of said main and auxiliary rolls defining between them a chamber, and means arranged adjacent to said auxiliary roll and feeding material to be ground thereto, said auxiliary roll feeding said material to said chamber and said main and auxiliary rolls kneading said material in said chamber to homogenize 10 said material upon rotation of said main roll.
